[57] CLAIM

The ornamental design for game board, as shown and described.

DESCRIPTION

FIG. 1 is a top perspective view of a game board showing my new design;

FIG. 2 is a bottom perspective view thereof;

FIG. 3 is a top plan view thereof;

FIG. 4 is a left side elevational view thereof; the right side elevational view being a mirror image thereof;

FIG. 5 is a front elevational view thereof; the rear elevational view being a mirror image thereof;

FIG. 6 is a sectional elevational view thereof; taken on line 6—6 of FIG. 3;

FIG. 7 is a bottom plan view thereof;

FIG. 8 is a top plan view of a second embodiment of FIG. 1;

FIG. 9 is a top plan view of a third embodiment of FIG. 1;

FIG. 10 is a top plan view of a fourth embodiment of FIG. 1;

FIG. 11 is a top plan view a fifth embodiment of FIG. 1;

FIG. 12 is a top plan view of a sixth embodiment of FIG. 1;

FIG. 13 is a top plan view of a seventh embodiment of FIG. 1;

FIG. 14 is a top plan view of a eighth embodiment of FIG. 1; and,

FIG. 15 is a top plan view of a ninth embodiment of FIG. 1.

The bottom surface of the embodiments in FIGS. 8 through 15 is similar to as shown in FIG. 7 of the first embodiment.
